S. J. VESELY

SHOCK ABSORBER

Filed Oct. 27. 1921

Inventor
Stanley J. Vesely
By J. M. G. John
Atty.

UNITED STATES PATENT OFFICE.

STANLEY J. VESELY, OF CEDAR RAPIDS, IOWA.

SHOCK ABSORBER.

Application filed October 27, 1921. Serial No. 510,738.

To all whom it may concern:

Be it known that I, STANLEY J. VESELY, a citizen of the United States, residing at Cedar Rapids, in the county of Linn and 5 State of Iowa, have invented certain new and useful Improvements in Shock Absorbers; and I do hereby declare the following to be a full, clear, and exact description of the invention, such as will enable others skilled in 10 the art to which it appertains to make and use the same.

This invention relates to the springs of motor vehicles, particularly automobiles, and has more especial reference to shock-absorbers 15 of a type set forth in Letters Patent No. 1,384,545, issued to me on the twelfth day of July, 1921.

In the patent referred to, the shock-absorber was more especially designed for that 20 type of motor vehicles in which the body springs are mounted parallel with the axles. The object of this invention is to adapt such a shock-absorber for use in connection with the other class of springs, disposed cross- 25 wise of the axles.

The invention is fully disclosed in the description and claims following, reference being had to the accompanying drawing, in which:

30 Fig. 1 is a side elevation of a device embodying my invention, the principal parts thereof being in section in the line 1—1 of Fig. 2. Fig. 2 is a vertical section of the same in the line 2—2 of Fig. 1, looking to the left. Fig. 3 is a plan view below the line 3—3 of Fig. 2.

The shock-absorber itself is practically the same as that described in the patent above referred to, but modified to meet the requirements of the other type of spring. It 40 comprises a pair of coil-springs 5 mounted in a pair of spring-barrels 6 connected by a yoke 7, which is adapted to be clamped to a vehicle axle. The springs are held between 45 washers 8, which have a limited movement in the barrels, by bolts 9, which at their upper ends connect with a bridge 10. The bridge slides up and down in slots 11 in the

spring barrels. In the patent referred to the spring is connected with this bridge. 50 This invention contemplates its connection with either a spring, of which 12 represents the lower member, or a part of the frame 13, as shown. In either case it is preferred to hang the part below the bridge and the same 55 is accordingly arched at 10^a to admit the connecting member. It is also provided with a pair of depending lugs 10^b to support said member by means of a cross-pin 14. For connection of the lower spring a bearing- 60 plate 15 is provided, which fits the top of the yoke, and is bolted thereto at 16, the same holes being used that are otherwise employed for clamping the absorber to an axle by stirrups. This bearing-plate is provided 65 with vertical lugs 15^a to receive a spring-pin 17.

By this simple device the shock-absorber is adapted for any ordinary type of vehicle spring, however disposed with respect to the 70 body of the vehicle.

Having thus described my invention, I claim:

1. A shock-absorber, comprising a pair of separated springs, slotted housings for said 75 springs, a connecting yoke, spring-receiving lugs projecting upwardly from the yoke, and a bridge, slideable in said slots, and bearing on the pair of springs, provided with depending lugs to engage an upper member. 80

2. A shock-absorber, comprising a pair of separated compression springs, slotted housings therefor, a connecting yoke, a lower-spring bearing-plate with upstanding lugs connecting with the yoke, an upper bridge 85 slideable in the housing slots, and having depending lugs to engage an upper member, and pins to connect the spring members with the bearing-plate and bridge.

In testimony whereof I affix my signature 90 in presence of two witnesses.

STANLEY J. VESELY.

Witnesses:

S. V. SHONKA,
P. A. VESELY.
